UNITED STATES PATENT OFFICE.

LOUIS L. DRIGGS, OF NEW YORK, N. Y.

SEMI-AUTOMATIC GUN.

1,393,353,

Specification of Letters Patent. Patented Oct. 11, 1921.

Application filed June 9, 1917. Serial No. 173,808.

To all whom it may concern:

Be it known that I, LOUIS L. DRIGGS, a citizen of the United States, residing at New York, in the county of New York and 5 State of New York, have invented certain new and useful Improvements in Semi-Automatic Guns; and I do hereby declare the following to be a full, clear, and exact description of the invention, such as will enable others skilled in the art to which it 10 pertains to make and use the same.

My present invention relates to improvements in semi-automatic guns, and it is intended to provide an anti-aircraft gun of 15 medium caliber, such as from two and a half to four inches, which may be fired at a high elevation and impart to the projectile a high initial velocity, and in which the breech mechanism may be readily operated 20 either by hand or semi-automatically.

My invention is more especially intended to provide an improvement on the general type of gun shown in my Patent No. 996,569, of June 27, 1911, entitled "Improvements in 25 semi-automatic guns."

My invention will be more clearly understood after reference to the accompanying drawings, in which the same parts are indicated by similar reference symbols throughout the several views.

Figure 1 shows a side elevation of the gun, and the upper portion of the mount, parts being broken away;

Fig. 2 is a rear elevation of the gun and 30 mount;

Fig. 3 shows a central horizontal section through the axis of the bore with the breech block in the closed position, parts being shown in elevation;

Fig. 4 shows a similar view to Fig. 3, but with the breech block in the open position, and the cartridge case partly drawn to the rear;

Fig. 5 shows a central section through the 45 breech of the gun, and the breech block chamber, all the mechanism being removed therefrom;

Fig. 6 shows a plan view of the breech block, with all the mechanism removed 50 therefrom;

Fig. 7 shows a central horizontal section through the breech block, with all the mechanism removed therefrom;

Fig. 8 shows a plan view of the main bolt, with the operating lever and the han-

dle for operating the same by hand, the view being broken away partly in section along the broken line 8—8 of Fig. 9;

Fig. 9 is a side elevation of the main bolt and operating lever and cams shown in Fig. 60 8, the upper portion being shown partly in section along the line 9—9 of Fig. 8, and looking in the direction of the arrows;

Fig. 10 shows a similar view to Fig. 8, with the handle removed; 65

Fig. 11 shows a section along the line 11—11 of Fig. 9, and looking in the direction of the arrows;

Fig. 12 shows a section along the line 12—12 of Fig. 9, and looking in the direction of the arrows; 70

Fig. 13 shows a plan view of the cam bracket and the cams mounted therein, as detached from the gun;

Fig. 14 shows a section along the broken 75 line 14—14 of Fig. 13, and looking in the direction of the arrows; the main bolt and semi-automatic operating arms being shown in dotted lines;

Fig. 15 shows an end view of the breech 80 block and extractors with a portion of the cartridge case, the breech block being shown partly in section along the broken line 15—15 of Fig. 6, and looking in the direction of the arrows; and shows the cocking lever and pivot pin for the same in place on the breech block; 85

Fig. 16 is a detail showing in perspective the pivot pin of the cocking lever;

Fig. 17 shows on a larger scale certain 90 details of the firing mechanism, the breech of the gun being shown in section along the line 17—17 of Fig. 3;

Fig. 18 shows a section along the broken 95 line 18—18 of Fig. 17;

Fig. 19 shows one of the removable blocks for forming part of the journal bearing for the main bolt;

Fig. 20 is a detail showing a side elevation of the extractor; 100

Fig. 21 shows a plan view of the lower one of the extractors; and

Fig. 22 is a rear elevation of one of the extractors as removed from the gun.

The gun body 1 is mounted in the slide 105 or cradle 2, provided with trunnions 3 supported on the yoke 4, which is inclined rearward, or goose necked as at 5, to permit the greater elevation of the gun. Said yoke is rotatably mounted on any suitable mount, 110

such as the pedestal mount 6, and may be clamped at any desired position in azimuth by the clamp 7.

- The slide is provided with two bands 8 and 9 to engage the recoil cylinder 10, which cylinder is mounted on top of the gun instead of at the bottom, as has been the most frequent practice heretofore, in order to permit the gun to be turned to a high elevation. 10 If the recoil cylinder be placed beneath the gun, as heretofore, it would strike the mount before the gun could be brought to a high elevation.

The recoil cylinder is rigidly secured to the slide in any convenient way, as by means of the collar 11 and head 12. The piston rod 14 of the recoil cylinder projects rearward, and has its end screw threaded to engage the lug 13, projecting upward from the gun body. In order to screw the piston rod 14 into the lug 13, a suitable angular set collar 15 may be provided to enable the piston rod to be conveniently turned with a wrench and screwed home to the desired position, as shown in Fig. 1.

The gun body is provided near its breech with a transverse breech block chamber so arranged that the breech block may be slid horizontally therein, as shown in Figs. 1 to 5. This breech block chamber is open at the rear as at 17 for convenience in loading. The breech block chamber is provided with a rib 18, set at a slight angle with the axis of the bore of the gun, which engages the corresponding groove in the breech block and furnishes additional bearing surface to the breech block against rearward pressure when the gun is fired. The breech block chamber is provided with recesses 19 for the claws of the extractor, and 20 for the trunnions of the extractors.

One side of the gun body has a hook shaped arm projection 21 furnishing bearings 22 for the main bolt, the hook members 45 of which projection are slotted as at 23 to permit the passage of the operating lever, which is hereinafter to be described. This projection 21 is perforated horizontally as at 25 to receive the stem of the journal block for the main bolt, which will be hereinafter described, and is perforated vertically as at 26 to receive the lock for said stem, which will also be hereinafter described.

In rear of the breech block chamber the gun body is perforated vertically as at 27 and horizontally as at 28 (see Fig. 5), and is slotted as at 29, for reasons that will be hereinafter described.

The breech block 30, is shown in assembled relation in Figs. 1 to 4, and in detail, with all the parts removed therefrom, in Figs. 6 and 7. This breech block is of the horizontal sliding type, and is grooved at the loading edge as at 31 to facilitate loading, 65 and grooved and tapered at its forward edge

as at 32, so that the breech block may wedge the cartridge case home in the powder chamber.

The breech block is provided with a groove 33 to engage the rib 18 of the breech block chamber, in front of which groove is a rib 34 which abuts against the rib 18 and affords a bearing surface to the block against backward pressure.

In front of this rib 34 the breech block 75 has a plane surface 35, which is preferably at the same level as the bottom of the groove 33, to permit the play of the extractors; and forward of this plane surface is a groove 36 to engage one of the trunnions 37 of 80 the extractor 38. This trunnion 37 has a flat face 37^a, which is cammed into engagement with the shoulder 36^a on the breech block (see Fig. 6), owing to the engagement of the round face 37^b of the trunnion with 85 the cam face 36^b of the groove 36 in the breech block.

The opposite trunnion 39 of the extractor engages in the elongated groove 20 (see Fig. 5) in the wall of the breech block chamber 90 of the gun. The extractor is provided with a laterally projecting web 40 (see Figs. 20 to 22), terminating in the claw 41. This claw projects into the recess 19 (see Fig. 5) when the cartridge case is shoved home in 95 the powder chamber of the gun.

The breech block is also provided with a cam groove 42, see Figs. 3, 4, 6 and 7, to engage the T-head 43, of the operating lever 44, which is rigidly attached to, or preferably integral with, the main bolt 45, journaled in the bearings 22 at one side of the gun. These bearings are slotted as at 23 to permit the passage of this operating lever 45; and to hold the main bolt securely in 105 place, I provide auxiliary bearing blocks 46, shown in assembled relation in Figs. 2, 3, and 4, and in detail in Fig. 19.

These blocks have a bearing surface 47 to engage the main bolt 45, and there are 110 preferably two of these blocks, one above and the other below the operating lever 44. In order to hold these blocks in place, I provide for each block a stem 48, which is notched as at 49, and this stem projects into the recess 25 in the projection 21. This stem is locked in place by the pin 50, which is screwed into the socket 26, see Fig. 5, and engages in the notch 49 of the stem 48. Thus the blocks 46 will be held in place 120 against being dislodged backward.

It will be noted that the pressure on the main bolt will be almost wholly in the forward direction, and that these blocks will merely serve as keepers for the main bolt. 125 This main bolt is journaled across one side of the gun as just described, and carries at one end, preferably the bottom, the various parts whereby the same is operated automatically, and at the other end, preferably 130

the top, the means for operating said main bolt by hand. It is desirable to have the latter at the top for convenience of access to the gun's crew, and to have the automatic gear 5 at the bottom so that it is thus out of the way, and also is more or less protected by the body of the gun and the parts of the mount from injury by broken pieces of projectiles or shrapnel fire, or the like.

10 It will be more convenient to describe the hand operation first. 51 is a hand lever, which is provided with a boss 52 loosely mounted on the upper end of the main bolt 45 and preferably held thereon in any convenient way, as by means of the cap 53 and the screw 54. This hand lever 51 is provided with a handle 51^a.

The body of the hand lever 51 is perforated to receive the locking bar 55, which 20 is provided with a locking head 56 adapted to engage a notch 57 in the main bolt 45, as shown in Figs. 8 and 9. This locking head 56 is normally held out of engagement by the spring 58 bearing against the collar 25 59 on the locking bar 55. This collar 59 carries an upwardly projecting arm 60, and a downwardly projecting lug 61, which lug is pressed into engagement with the catch 62 mounted on the breech of the gun, as 30 shown in assembled relation in Fig. 2 and in detail in Figs. 8 and 9.

When this bar is normally pressed outward by the spring 58, the locking head 56 will be clear of the main bolt 45, and the 35 catch 62 will hold the hand lever in the fixed position, so that the gun may recoil and move forward again, and may be operated automatically or semi-automatically without any swinging around of the hand 40 lever; but if it is desired to operate by hand, by gripping firmly on the handle 51^a and the arm 60, the hand lever will be thrown into operative relation and the main bolt may be rotated by hand in the usual way, 45 causing the operating lever 44 to move the breech block to the open or to the closed position, as may be desired, and at the same time operating the extractors and the various other parts of the mechanism, as will 50 be hereinafter more fully described in connection with the operation of the gun.

Reverting now to the parts for operating the gun semi-automatically, 63 represents a cylindrical shell, preferably open at its rear 55 end, attached to the gun at one side. In this shell is mounted a stout coil spring 64, which bears at one end against the closed head of said cylinder, and at the other end against the piston or washer 65 adjustably 60 secured on the rod 66 by means of the nuts 67. The tension of this spring may be adjusted by screwing up, or easing off on these nuts.

The rear end of this piston rod 66 is connected by the chain 68 to the lug 69, see

Figs. 3, 4, 9 to 12, carried by the arm 70 of the block 71, which is secured fast to, or integral with, the main bolt 45. This block 71 carries two other arms, one of which 72 carries the downwardly projecting lug 73, 70 and the other arm 74 carries the stop lug 75, which coacts with the yielding cam block, as will now be described.

The cam block 76, shown in assembled relation in Figs. 1 and 2, and in detail in 75 Figs. 13 and 14 is mounted on a bracket 77 attached to the slide 2. This bracket is provided with a slideway 78, in which the inverted T-bar 79, attached to the breech of the gun, slides when the gun moves backward and forward on recoil and counter recoil.

The cam block 76 is provided with two lugs 80 and 81, projecting upwardly therefrom, as shown in Figs. 13 and 14, which 85 lugs engage respectively the lugs 73 and 75 of the block 71, as indicated in Fig. 14.

The cam is normally rotated in one direction by the spring 82, and in the reverse direction by the lug 73 engaging the lug 90 80; but the coaction of the rotary cam with the lugs 73 and 75 carried by the block 71 is fully described and claimed in my Patent No. 996,569, granted June 27, 1911, and entitled "Semi-automatic guns," and will 95 not be further described herein.

The cover 83 of the housing, inclosing the cam block, and with it the cam block itself may be held in either the operative or the inoperative position by means of the plunger 84 (see Fig. 14); but this is fully described and claimed in my patent, aforesaid, and does not constitute a part of my present invention.

The firing mechanism, shown more clearly 105 in Figs. 1, 3, 4, 17 and 18, comprises the firing pin 90, which is normally pressed forward by the spring 91 and is thrown back by the head 92 of the cocking lever 93, which is in the form of a bell crank lever 110 pivoted at 94 and having its short arm 95 engaging the toe 96 of the sear block 97, which is journaled to one side of the breech of the gun, as shown in Fig. 17.

This sear block is normally returned to 115 the initial position by means of the spring plunger 98 shown in Figs. 17 and 18, which engages a notch 99 on the boss 100 of the sear block 97. This boss is provided with an arm 101 having a rounded head 102 engaging in the yoke 103 provided in the end of the firing lever 104, which lever is pivoted beneath the gun as at 105 and has its outer end enlarged as at 106 to engage the rod 107, which may be pushed backward 120 by the trigger 108; thus it will be seen that the spring plunger 98 normally tends to restore both the sear and the trigger to the initial position, and pulling on the trigger 125 will force this spring plunger backward and 130

release the toe of the sear. By having the spring plunger housed in the body of the gun it is protected from exposure, dust, etc., and may be conveniently kept in repair.

5 The spring plunger 98 consists of two cylindrical blocks 98^a connected together by a stem 98^b and pressed on by a spring 98^c, and when the plunger is in the operative position it engages any one of these blocks 10 98^a and projects into an arc-shaped groove 100^a in the boss 100, as shown in dotted lines in Fig. 17 so that the sear piece cannot be removed; but if the plunger be pushed inward so that the stem 98^b registers with the 15 groove 100^a, the sear piece may be readily drawn outward, the toe 96 in that case passing along the groove 27^a in the breech of the gun, as shown in Figs. 3 and 5. Thus this 20 spring plunger serves as a lock to hold the sear piece in place in the gun, and also as a means for restoring the sear and the trigger to the firing position.

Supposing the parts to be in the position shown in Fig. 3, by pulling the trigger the 25 firing pin will fly forward and hit the primer; now, if the breech block be moved to open position, either by hand or automatically, the arm 95 of the cocking lever will ride past the toe 96 of the sear and the 30 firing pin will remain in the position shown in Fig. 4; when the breech block is returned to the closed position the arm 95 will engage the toe 96 and will pull back the firing pin, restoring the same to the cocked position 35 shown in Fig. 3.

It will be seen that if we pull on the heel of the firing pin, when the parts are in the position shown in Fig. 4, it will be necessary to pull the firing pin back a considerable distance before the opposite end of the slot engaging the head 92 of the cocking lever will engage the back of said cocking lever and start same to the cocked position. To avoid this lost motion I provide a hook 45 92^a, carried on the back of the cocking lever, which may be engaged by a hook or lanyard, or other suitable implement, and the firing pin and cocking lever may both be brought simultaneously back to the cocking position 50 shown in Fig. 3.

The cocking lever 93 is mounted in a slot 93^a in the breech block, as shown more clearly in Figs. 2, 7 and 15. This cocking lever is pivoted on a pin 110, which is shown 55 in detail in Figs. 15 and 16, in which the pin proper is provided with a resilient arm 111 having a laterally projecting lug 112 adapted to snap into an annular groove 113, which forms an extension of the bore 114 in which 60 the pin 110 is mounted. This resilient arm 111 is provided with an eye 115, so that it may be engaged by a hook or lanyard and lifted out of engagement with the groove 113, and the pin 110 may be withdrawn, 65 thus rendering it an easy matter to assem-

ble or disassemble the cocking lever from the breech block.

The slide 2 is provided with a laterally projecting bracket 120, provided with a rearwardly projecting arm 121, which is intended to be held beneath the left arm of the gun pointer, so that he may conveniently look over the sights 122, and his right hand may conveniently grip the hand grip 108^a and the trigger 108. 123 represents a guard to protect the parts against injury in loading.

The gun is elevated by means of the hand wheel 125; whose handle 126 can be grasped by the left hand of the gun pointer. This hand wheel turns the bevel pinion 127, see Figs. 1 and 2, which in turn, turns the bevel gear 128 and rotates the worm 129, which worm meshes with the segmental worm rack 130 secured to the side of the slide, as shown in Figs. 1 and 2.

It will be seen that the gun is turned entirely in azimuth by the arm 121 while it is elevated and depressed by means of the hand wheel 125, thus the same gun pointer 90 can conveniently swing the gun in azimuth and elevate and depress the same.

It will also be noted that the elevating gear serves as a stop to the downward whip of the breech of the gun when the same recoils, thus taking any down thrust off the shoulder of the gun pointer and retaining it on the slide. It is important with a light gun of this character to have a long recoil so as to render it possible to use a light 100 mount and lessen the back thrust of the trunnions, and when the gun has a long recoil there is a strong tendency of the breech of the gun to whip down, owing to the changed position of the center of gravity of the gun on the maximum limit of its recoil.

It will be noted that the pointing arm 121 is secured to the cradle as is also the rack 130, while the bracket which carries the worm 129 is secured to the yoke 4, and therefore any downward whip of the piece when fired is transmitted through the rack 130 to the worm 129 and is resisted by the yoke 4. There is thus no downward thrust at all thrown on the pointing arm.

The rearward trend or overhang of the goose-neck permits the gun to be pointed in almost a vertical direction.

The operation of the device is as follows: First, to operate by hand. Suppose the 120 breech to be closed, throw the cam 76 out of engagement and lock it with the plunger 84; grasp the handle 51^a of the hand lever and the arm 60, pressing the same together and causing the locking head 56, shown in Fig. 8, to engage with the groove 57 in the main bolt 45, and then swing the hand lever 51 by hand, to the position for opening the breech. This movement of the breech block will cause the operating lever 44 to swing 125 130

outward, further compressing the spring 64 in the casing 63. The extractor will rock on its front face, causing the extractor lug 39 to pass forward in the groove 20 in the 5 breech of the gun, and causing the extractor lug 37 to slide through the groove 36 in the top and bottom of the breech block until the flattened face 37^a slips over the shoulder 36^a on the breech block and holds the breech 10 block in the open position against the action of the spring 64 when the hand lever is released. There are two of these extractors, but both function in precisely the same way but on opposite sides of the breech block 15 chamber.

When the cartridge case is inserted the extractor will be tripped forward, releasing the breech block, and the spring 74 will restore the breech block to the closed position, 20 which action may be supplemented by the operator at the hand lever if desired, but it will ordinarily only be necessary to use the hand lever in opening the breech.

As the breech block returns to the closed 25 position, the arm 95 of the cocking lever will engage the toe 96 of the sear, and the firing pin will be cocked and the parts will assume the position shown in Fig. 3, when the gun 30 may be fired, and the cycle of operation may be repeated.

For semi-automatic firing it will, of course, be necessary to open the breech by hand for loading the first round, after which the piece may be operated by opening 35 and closing the breech by the automatic mechanism, which is controlled by the extractors, and these in turn are released by the insertion of the fresh cartridge case.

For semi-automatic firing, assuming the 40 first round to have been loaded and the parts to be in the position shown in Fig. 3, release the lock 84 for the cam 76, so that the cam may be in proper control of the spring 82 for semi-automatic fire.

45 Now, if the gun be fired, the arm 73 will coact with the arm 80 on the cam 76, pressing back the cam, allowing the gun to recoil to the rear, and on counter-recoil this arm 73 will engage the arm 80 and will rock the main bolt 45, causing the operating lever 44 to open the breech and at the same time to further compress the spring 64. The breech block will be held in this open position by the engagement of the extractor lugs 37 with 50 the shoulders 36^a, and the breech block will be held in the open position shown in Fig. 4 until a fresh cartridge case is inserted; the rim of this cartridge case will strike the claws of the extractors, throwing the lugs 55 37 out of engagement with the shoulders 36^a and allowing the breech block to be moved to the closed position under the action of the spring 64.

Now if the gun be fired again, the same 60 cycle of operations will take place.

In this semi-automatic firing it will only be necessary to use the hand lever 51 for the first loading, after which it is possible to continue to fire the gun semi-automatically indefinitely.

70 It will be obvious from the description herein, that the various parts may be assembled quickly and disassembled without the use of any special tools more than the ordinary screw driver, hook and wrench.

75 It will also be noted that the semi-automatic parts and most of the operating mechanism are out of the way of the gun's crew, while there is nothing to interfere with convenience in loading, pointing and firing 80 the gun. By having the breech bolt sliding horizontally, it will not be necessary to lift the same, as is the case with guns of the the Hotchkiss type, and therefore the load on the spring 64 is materially lessened.

85 By having the recoil cylinder mounted on top of the gun, it is also out of the way, and will not interfere with the elevating of the gun, as would be the case were it mounted beneath the same; and, moreover, it can be 90 more readily assembled in this position than when mounted beneath the gun.

95 It will be obvious that various modifications might be made in the herein described apparatus, and in the construction, combination and arrangement of parts which could be used without departing from the spirit of my invention.

Having thus described my invention, what I claim and desire to secure by Letters 100 Patent of the United States is:

1. The combination with a gun mount provided with a yoke swiveled thereto and inclined rearward therefrom, of a slide trunnioned in said yoke, a shoulder bar connected to said slide, a gun body slidably mounted in said slide and provided with an upwardly projecting lug near the breech thereof, a recoil cylinder secured to said slide above said gun body, and a recoil 105 cylinder piston, and piston rod, the said piston rod having its outer end secured to said lug, a segmental rack fast to said slide provided with worm teeth, a bracket carried by said yoke, a worm 110 journaled in said bracket and engaging said rack teeth, and means for turning said worm, substantially as described.

115 2. The combination with a gun mount provided with a yoke swiveled thereto and inclined rearward therefrom, of a slide trunnioned in said yoke, a shoulder bar connected to said slide, a gun body slidably mounted in said slide, and provided with an upwardly projecting lug near the breech 120 thereof, a recoil cylinder secured to said slide above said gun body, and a recoil cylinder piston, and piston rod, the said piston rod having its outer end screwed into said lug, a segmental rack fast to said slide pro-

vided with worm teeth, a bracket carried by said yoke, a worm journaled in said bracket and engaging said rack teeth, and means for turning said worm, substantially as described.

3. The combination with a gun mount provided with a yoke swiveled thereto and inclined rearward therefrom, of a slide trunnioned in said yoke, a shoulder bar connected to said slide, a gun body slidably mounted in said slide provided with a horizontally disposed breech block chamber provided with an upwardly projecting lug near the breech thereof, a recoil cylinder secured 10 to said slide above said gun body, a recoil cylinder piston, and piston rod, the said piston rod having its outer end secured to said lug, a horizontally sliding breech block and an operating lever hinged to the side of of the gun and engaging said breech block, with means for operating said operating lever, a segmental rack fast to said slide provided with worm teeth, a bracket carried by said yoke, a worm journaled in said bracket and engaging said rack teeth, and means for turning said worm, substantially as described.

4. The combination with a gun mount provided with a yoke swiveled thereto and 30 inclined rearward therefrom, of a slide trunnioned in said yoke, a shoulder bar connected to said slide, a gun body slidably mounted in said slide, provided with a horizontally disposed breech block chamber, 35 and also provided with an upwardly projecting lug near the breech thereof, a recoil cylinder secured to said slide above said gun body, a recoil cylinder piston, and piston rod, the said piston rod having its outer end secured to said lug, a horizontally sliding breech block, and an operating lever hinged to the side of the gun and engaging said breech block, with means for operating said operating lever either by hand or automatically, a segmental rack fast to said slide provided with worm teeth, a bracket carried by said yoke, a worm journaled in said bracket and engaging said rack teeth, and means for turning said worm, substantially as described.

5. The combination with a gun mount provided with a yoke swiveled thereto and inclined rearward therefrom, of a slide trunnioned in said yoke, a shoulder bar connected to said slide, a gun body slidably mounted in said slide, provided with a horizontally disposed breech block chamber, and 50

also provided with an upwardly projecting lug near the breech thereof, a recoil cylinder secured to said slide above said gun body, a recoil cylinder piston, and piston rod, the said piston rod having its outer end secured to said lug, a horizontally sliding breech block, and an operating lever hinged to the side of the gun and engaging said breech block, with means for operating said operating lever either by hand or automatically, said means comprising a main bolt journaled vertically at the side of the gun and rigidly connected to said operating lever, a hand lever mounted above the gun and loosely journaled on said main bolt, with means for rigidly connecting said hand lever to said main bolt when desired, a semi-automatic attachment carried by the slide and mounted below the gun body, and means carried by the lower end of said main bolt for actuating the semi-automatic mechanism after the gun is fired, a segmental rack fast to said slide provided with worm teeth, a 80 bracket carried by said yoke, a worm journaled in said bracket and engaging said rack teeth, and means for turning said worm, substantially as described.

6. In a breech loading gun of the character described, the combination with a gun body provided with hook shaped bearings projecting therefrom, of a main bolt journaled in said bearings and provided with an operating lever for the breech block, bearing blocks detachably connected to the gun for holding said main bolt in place in its bearings, each provided with a stem projecting into a recess provided in the gun, and means for locking said stem in place, 90 substantially as described.

7. In a breech loading gun of the character described, the combination with a gun body provided with hook shaped bearings projecting therefrom, of a main bolt journaled in said bearings and provided with an operating lever for the breech block, bearing blocks detachably connected to the gun for holding said main bolt in place in its bearings, each provided with a stem projecting into a recess provided in the gun, the said stem having a notch in one side thereof and a pin held in the gun and projecting into said notch, and thereby constituting means for locking said stem in place, 100 substantially as described.

In testimony whereof I affix my signature.

LOUIS L. DRIGGS.
